UNITED STATES PATENT OFFICE.

JOSEPH BERG, OF NEW YORK, N. Y.

BOOKBINDING.

Application filed January 13, 1926. Serial No. 80,873.

To all whom it may concern:

Be it known that I, JOSEPH BERG, a citizen of the United States, and a resident of the city, county, and State of New York, have invented a certain new and useful Improvement in Bookbindings, of which the following is a specification.

This invention relates to a binding for books and has for its object to provide such a binding which will be particularly applicable to check books, ledgers, or other books of account, where it is desirable to have the pages lie flat for convenience in writing or making entries in the book. 10 This is particularly true of check books, where entries have to be made upon the stubs at positions close to the binding, which at the present time is so rigid and inflexible that the leaves or pages will not lie flat and convenience in the use of the book is not found. 15

One of the main objects therefore, of my invention is to provide a permanent binding for a book which will afford an extreme flexibility, permitting the pages to lie flat when the book is open and which will also provide a strong and substantial binding in which the pages of the book are firmly and securely held. 25

With these objects and such other objects as may hereinafter appear, in view I have devised the particular arrangement of parts hereinafter set forth and more particularly pointed out in the claims appended hereto. 30

Reference is to be had to the accompanying drawing, forming a part hereof, in which—

Figure 1 is a sectional view through the book and its binding showing my improved construction. 40

Figure 2 is a perspective view of part of the back of the book with parts being broken away clearly disclose its construction; and 45

Figure 3 is a sectional view of a portion of the book showing the same as it appears when in an open position and disclosing the manner in which the pages lie flat. 50

Throughout the various views of the drawings, similar reference characters designate similar parts.

In the preferred embodiment of my invention as disclosed in the accompanying drawing, 1 indicates a series of leaves or

pages which go to make up the body of the book. These may be of any shape or size dependent upon the type of book under consideration and as stated heretofore, the invention is particularly desirable in connection with check books. It may be therefore, that the series of leaves 1 are pages of checks. These pages 1 preferably have their rear edges 2 united together by adhesively securing a strip 3 of an open mesh textile fabric to said rear edges. Said binding strip 3 therefore secures the leaves together so that they cannot be separated readily. Adjacent their rear edges 2, the pages are provided with a series of spaced perforations 4 and coil springs 5 pass through these perforations and hold the leaves together, thus co-operating with the binding strip 3 which is adhesively secured to the back edges of these leaves as was heretofore pointed out. 70

The springs 5 have their ends terminating in loops 6 and wires or rods 7 pass through these loops on opposite sides of the batch of leaves, thus holding the springs in place and resiliently holding the leaves together. 75

At 8 is shown the cover of the book and said cover has its back part 9 adhesively secured to the back edges of the sheets 2 and over the fabric binding strip 3. Parts 10 of said cover also embrace the sides of the leaves and are also secured adhesively or otherwise thereover, at the same time overlying the ends of the springs 5 and the wires 7 which extend through said springs. 80

From the foregoing, the manner in which the book is used is readily apparent.

In Figure 3, the book is shown in an open position, where it will be seen that the springs 5 possesses such resiliency that they permit the leaves to separate to a great extent and enable them to lie out perfectly flat when the book is in an open position. 95 The means for permanently securing together the rear edges of the leaves consisting of the adhesively secured fabric strip 3 and the back and side parts 9 and 10 of the cover makes a very secure yet flexible joint 100 and cooperates with the springs to secure the desired result. Such adhesive securing of the leaves at their rear edges prevents said leaves from being pulled out through the springs 5 should an accidental or sudden pull or tug on one of the leaves take place. Without the use of the adhesive 105 110

securing means on the back of the leaves, said leaves would readily pull through the coils of the springs and be cut by the wire forming said springs and thus become readily detached from the book.

The construction presented by applicant avoids this by securing the leaves in such manner as to resist a longitudinal pull upon the leaves and yet permit the leaves to readily separate and lie perfectly flat when the book is open.

Having described one embodiment of my invention, it is obvious that the same is not to be restricted thereto, but is broad enough to cover all structures coming within the scope of the annexed claims.

What I claim is:

1. A binding for books consisting of a plurality of pages having their rear edges adhesively united, said sheets being perforated near said rear edges, springs located in said perforations, wires extending through the ends of said springs on opposite sides of the pages, and a cover adhesively secured over the rear edges of the pages and over the ends of the springs and the wires.

2. A binding for books consisting of a plurality of pages, means for permanently securing together the rear edges of said pages, perforations in said pages, separate coil springs extending through said perfo-

rations, wires extending through the ends of said springs on opposite sides of the pages, a cover having its back secured to the rear edges of the pages and its sides 35 extending over the coil springs and wires.

3. A binding for books consisting of a plurality of pages, a strip of binding fabric secured along the rear edges of said pages and uniting the same, perforations in said 40 pages, separate elastic members extending through said perforations, and a cover embracing the rear ends of the pages and adhesively secured to their edges and over the ends of the elastic members.

4. A binding for books consisting of a plurality of pages, a strip of fabric secured adhesively along one edge of said pages and uniting the same, said pages being perforated near said edge, separate coil springs 50 located in said perforations, a continuous wire extending through the ends of said springs on each side of the batch of pages, a cover secured over said pages and having its back adhesively secured over the strip of 55 fabric which united the sheets and its sides adhesively secured over the ends of the springs and the wires extending through the same.

Signed at the city, county and State of 60
New York, this 11th day of January, 1926.

JOSEPH BERG.
